UNITED STATES PATENT OFFICE.

SOLOMON HEILNER, OF NEW YORK, N. Y.

CORSET.

SPECIFICATION forming part of Letters Patent No. 268,794, dated December 12, 1882.

Application filed September 20, 1882. (No model.)

To all whom it may concern:

Be it known that I, SOLOMON HEILNER, of the city, county, and State of New York, have invented a new and useful Improvement in Corsets, of which the following is a specification, reference being had to the drawings accompanying and making part thereof.

My invention applies to that part of the corset which consists of the opening through the length of the corset at the back, and which is usually closed by lacing-cords drawn through eyelet-holes in the corset at or near the two edges of the opening, and which cords, passing from one side to the other of the opening, draw and secure the two edges together; and it consists in the construction of a protector of a separate part of elastic materials and cloth, similar to the elastic materials and cloth of the body of the corset, of sufficient length to extend over the opening in the back of the corset and widening from top to bottom, so as to be slightly wedge-shaped, and connected to the corset only by the lacing-cords passing through eyelets in this separate part and on the edges of the corset-opening, so that by the adjustment of the cords the opening at the back can be adjusted to a greater or less width at the lower or upper portion, as may suit the shape and comfort of the wearer.

In the accompanying drawings, in Figure 1, the outline of the back of the corset is shown with the opening and eyelets near the edges, but without the lacing-cord attached. In Fig. 2 is shown a view of the separate part or wedge-shaped piece, which is a protector intended to cover the opening at the back of the corset, the eyelet-holes by which it is to be held in place being shown in their proper positions. In Fig. 3 is a representation of the opening of the corset at the back and the protector in place thereon, and the lacing ends drawn through the eyelets.

A represents the body of the corset at the back, having the opening with the eyelet-holes *a* near the edges of the opening.

B represents the protector, which, gradually widening from top to bottom, is slightly wedge-shaped. The object of widening this protector toward the lower part is to admit of its covering a somewhat wider opening of the corset at

the bottom than at the top, which is requisite to adapt the corset to the form or figure of the wearer. In this protector B are the four pairs of eyelet-holes, *b b' b*, one pair near each end and two pairs near the middle between the two ends, as shown in the drawings. The separate piece B need not necessarily be of the same material as the corset-body; but it may be made of flannel and cloth, or any suitable material and elastic substances. The protector B is attached on the under side of the opening of the corset by the lacing-cord C, which draws and secures the two edges of the corset together in the usual manner, excepting that at the top and bottom the lacing-cord is drawn through the two eyelet-holes *b* and across the space between them, and thence into the corresponding eyelet-holes, *a*, on the edges of the opening, and on the middle eyelet-holes the lacing-cord is drawn through one pair of the eyelet-holes, *b'*, as it crosses from one edge to the other, and also through the other pair of eyelets, *b*, as it crosses to the opposite edge. The lacing-cord C, where it passes through the middle eyelets, *b' b'*, being long enough, is drawn out, so as to afford loose double strings for adjusting and tying the end, so as to adjust the opening over the protector B, as may be desired. By this construction and arrangement the lower portion of the corset may be considerably widened, as shown in Fig. 3, without leaving any open space between the two edges, the space being always filled by the protector B, and in like manner the upper part may be widened, when desired. The point of fastening, being midway between the top and bottom, admits of the opening being enlarged at either end.

By this improved construction of the corset the adjustment to the form of the wearer is facilitated and the enlargement of the corset provided for without exposing that part of the body of the wearer to the sensation of cold from the widening of the opening, and the elasticity and flexibility of the protector B adapts itself to the back and the movement of the body of the wearer independently of the stiff edges of the opening of the corset, and lends an easy and pleasant support to the spinal column.

The principal feature of my invention herein set forth is the protector B, and therefore

while I claim the manner within described* of connecting the same with the opening of the corset, yet I am aware that other means may be adopted for connecting each separate piece by a lacing-cord to the opening without departing from the principal feature of my invention.

What I claim as my invention, and desire to secure by Letters Patent, is—

1. In combination with a corset, the protector B, in a separate piece, adapted to cover the opening in the back of the corset, and adapted to be adjusted and to be held in place by the lacing-cord C, passed through the protector, as shown, substantially as set forth.

2. In combination with a corset, the protector B, in a separate piece, made wider at the bottom than at the top, and having the pairs of eyelets b b' b', the protector being adapted to cover the opening in the back of the corset when the latter is adjusted to form a wider opening at the bottom than at the top, and to be held in place by the lacing-cord C, passed through the eyelet-holes, substantially as set forth.

SOLOMON HEILNER.
